UNITED STATES PATENT OFFICE.

WILLIAM F. BURNETT, OF HEISSON, WASHINGTON.

CAN-COVER.

1,000,373.

Specification of Letters Patent. Patented Aug. 15, 1911.

Application filed April 26, 1911. Serial No. 623,407.

To all whom it may concern:

Be it known that I, WILLIAM F. BURNETT, a citizen of the United States, residing at Heisson, in the county of Clarke and State 5 of Washington, have invented certain new and useful Improvements in Can-Covers, of which the following is a specification, reference being had to the accompanying drawings.

10 This invention relates to improvements in can covers and more particularly to a cover for milk cans, the invention having for its primary object the provision of very simple means whereby the ejection of the milk when 15 the cover is inserted into the top of the can owing to the displacement of air, is entirely obviated.

The invention has for a further object the provision of a device for the purpose specified which is extremely simple and efficient 20 in construction, may be manufactured at small cost and is admirably adapted for overcoming the undesirable feature of the present form of can cover as above noted.

25 With the above and other objects in view, the invention consists of the novel features of construction, combination and arrangement of parts hereinafter fully described and claimed, and illustrated in the accompanying drawings, in which—

30 Figure 1 is a top plan view showing the movable closure plate in open position; Fig. 2 is a section taken on the line 2—2 of Fig. 1; and Fig. 3 is a detail perspective view of 35 the movable plate.

Referring in detail to the drawing 5 designates a milk can of the ordinary form, and 6 indicates my improved cover. This cover consists of the top plate 7 having an 40 annular depending flange 8 which is adapted to fit within the upper open end of the can and closely engage the cylindrical wall thereof. The cover is further provided with an outwardly flared circumscribing flange 9 45 which extends above and over the upper edge of the can.

A plate 10 is pivotally mounted upon the upper surface of the top 7 of the can cover, the pivot 11 being eccentrically disposed 50 through said top plate. The plate 7 of the cover is also provided at or adjacent to its center with an opening 12 which is normally adapted to be closed by the pivoted plate 10. This plate lies closely upon the surface 55 of the top plate 7 and extends to the edge thereof, the end of the pivoted plate 10 be-

ing angularly bent as indicated at 10' and also closely engaged with the inner surface of the flared flange 9 of the cover, the extremity of said plate being bent over the 60 outer edge of said flange as indicated at 13. The flange 9 is provided with an opening 14, and the angular portion 10' of the pivoted plate 10 also has an opening 15 therein which is adapted to register with the opening 14 when the plate is in position over the air vent opening 12. These alined openings are adapted to receive the hasp of a suitable padlock so as to retain the pivoted plate in its closed position as shown at 18 in Fig. 70 2. Lugs 16 are provided upon the upwardly and outwardly flared annular flange 9 of the can to limit the pivotal movement of the plate 10, said plate having a suitable finger-piece 17 secured thereto by means of which 75 it may be conveniently moved.

In the practical operation of the device, when the cover is to be inserted into the top of the can, the plate 10 is moved to the position shown in Fig. 1 and the vent opening 80 12 uncovered. The depending annular flange 8 of the can top is then inserted into the open top of the can and as it is forced downwardly into the same, the air which is displaced escapes through the vent opening 12. It 85 will be obvious that when the can has been filled almost to the limit of its capacity, the air pressure which is caused by forcing the cover into the can will displace part of the contents, and as no escape is provided for 90 this air, the milk will be forced out of the top of the can between the rim or edge thereof and the flared flange 9 of the can cover, thereby not only wasting the milk 95 but also spattering the clothes of the milk man. By means of my improved can cover, these defects are entirely overcome and a device provided whereby the air is permitted to escape from the can as the cover is inserted therein. After the cover has been 100 placed in position, the movable plate 10 is locked thereon as previously described to close the vent opening and prevent the entrance of dirt or other foreign material into the can. The can cover is also provided 105 with the usual handle 19 whereby it may be readily lifted or placed in the open end of the can to close the same.

From the foregoing it is thought that the construction and operation of my device 110 will be readily understood. It is simple, durable, and highly efficient for the pur-

pose in view. Owing to its extreme simplicity it will further be obvious that the device can be manufactured at a very low cost.

5 While I have shown and described the preferred construction and arrangement of the various parts, it will be understood that the device is susceptible of considerable modification without departing from the essential feature or sacrificing any of the advantages of the invention.

Having thus described the invention what is claimed is:—

1. The combination with a can, of a cover 15 having an annular depending flange to fit into the top of the can and an outwardly and upwardly flared annular flange, the top of the cover having a vent opening therein, a plate pivoted at one end upon the cover 20 and extending upon said flared annular flange, stops to limit the pivotal movement of said plate in either direction, and means engaged with said flared flange and the plate when the latter is disposed over the 25 opening in the can top, to lock said plate against movement.

2. The combination with a can, of a cover having a depending flange to fit into the open end of the can, said cover also having 30 an outwardly and upwardly flared annular flange, the top of the cover having a vent opening therein, a plate movable upon the cover adapted to be disposed over said

opening to close the same, the free end of said plate engaging upon the flared flange 35 of the cover, said flange having an opening therein, said plate being also provided with an opening to register with the opening in said flange when the plate is disposed over the vent opening of the cover, and means 40 engaging in said registering openings to lock the plate in its closed position.

3. The combination with a can, of a cover therefor having an annular depending flange to fit into the top of the can and an 45 upwardly and outwardly flared annular flange, the top of the cover having an opening therein, a plate eccentrically pivoted at one of its ends upon said cover and movable over said opening to close the same, the 50 other end of said plate extending upon said flared annular flange, stops arranged on said flange to limit the movement of said plate, the extremity of the plate engaging over the edge of the flange, said plate and flange each having an opening therein 55 adapted to register when the plate is in its closed position to receive a suitable locking element.

In testimony whereof I hereunto affix my 60 signature in the presence of two witnesses.

WILLIAM F. BURNETT.
